DESIGN FOR A MEDICAL EQUIPMENT STAND

Victor A. Noel, Brighton, and Edwin D. Beebe,
Rochester, N. Y., assignors to Ritter Company,
Inc., New Castle County, Del., a corporation of Delaware

Application September 13, 1941, Serial No. 103,344

Term of patent 14 years

To all whom it may concern:

Be it known that we, Victor A. Noel and Edwin D. Beebe, both citizens of the United States, residing at Brighton and Rochester, respectively, in the county of Monroe, and State of New York, have invented a new, original, and ornamental Design for a Medical Equipment Stand, of which the following is a specification, reference being had to the accompanying drawings, forming part thereof.

Fig. 1 is a front elevational view of a medical equipment stand showing our new design;

Fig. 2 is a side elevational view thereof as viewed from the left in Fig. 1, and

Fig. 3 is a side elevational view of the same as viewed from the right in Fig. 1.

We claim:

The ornamental design for a medical equipment stand, substantially as shown.

VICTOR A. NOEL
EDWIN D. BEEBE.
